UNITED STATES PATENT OFFICE.

FRED E. GREENE, OF BERKELEY, CALIFORNIA.

MACHINE FOR FINISHING AND PAVING DITCHES.

Application filed August 23, 1924. Serial No. 733,856.

To all whom it may concern:

Be it known that I, FRED E. GREENE, a citizen of the United States, residing at Berkeley, county of Alameda, and State of California, have invented new and useful Improvements in Machines for Finishing and Paving Ditches, of which the following is a specification.

This invention relates to a mechanism for 10 finish grading a ditch and thereafter lining the same with a coating of substantially water-proof material for preventing the seepage of water therethrough. The primary object of the invention is to provide 15 a machine for performing these functions with facility.

It is known that certain soils are not well adapted to hold water, and a considerable portion of the water carried in ditches 20 through such soils is lost through seepage. This is particularly true in dry, sandy soils, where irrigation becomes necessary, and where water is not exceedingly plentiful, this seepage amounts to a considerable loss. 25 Such loss may be prevented by lining or paving the surface of these ditches with a substantially water-proof material, such as asphalt or concrete. It is an object of my invention to provide a continuously operating 30 machine adapted to straddle such a ditch and finish grade and line the same as the machine passes therewith.

With the above and other objects in view, my invention consists in the features of construction and operation set forth in the following specification and illustrated in the accompanying drawings. In such drawings, annexed hereto and forming a part of this 35 specification, I have shown certain specific mechanism, but it will be understood that my invention is not to be defined and limited thereby, but the invention can be modified within the scope of the appended claims.

Referring to the figures of the drawing, 40 Fig. 1 is a general plan view of my machine;

Fig. 2 is a side elevation thereof on a larger scale, parts of the frame being broken away;

Fig. 3 is a plan view of the front end of the machine which carries the endless scrapers hereinafter described;

Fig. 4 is an elevation thereof;

Fig. 5 is a plan view of the intermediate portion of the machine which carries the 55 finishing scraper hereinafter described;

Fig. 6 is an elevation thereof;

Fig. 7 is an enlarged fragmentary plan view taken on line 7-7 of Fig. 6;

Fig. 8 is a transverse section taken on line 60 8-8 of Fig. 7;

Fig. 9 is a transverse section taken on line 65 9-9 of Fig. 7;

Fig. 10 is a detail view taken on line 10-10 of Fig. 7;

Fig. 11 is a detail view taken on line 11-11 of Fig. 7;

Fig. 12 is a detail view of a portion of the driving mechanism hereinafter described.

Fig. 13 is an elevation of the rolling mechanism carried by the rear end of the frame. 70

My present invention does not deal with the original forming of the ditch, such original or rough forming of the ditch being accomplished by well-known power scraping 75 methods. Header-boards or tracks are thereafter provided along the two edges of the ditch, and in operation my machine is run at a low speed along these tracks. The mechanism, preferably in the form of endless scrapers, is provided on the forward end of the machine for finish grading the sloping portions of the ditch and removing the excess soil. A second mechanism, preferably in the form of a scraping blade under control 80 of an operator, follows the endless scrapers and finish grades the entire surface of the ditch. After the passage of this mechanism, a third mechanism on the rear of the machine rolls the surface of the ditch to compress the 85 same to a smooth, uniform level. Power means is provided for moving the machine along the ditch, and it should be understood that this is preferably a slow, continuous movement, and that the grading operation 90 is performed and completed at one passage of the machine along the ditch.

After the ditch has been graded and rolled, as above described, the same machine is again passed along the ditch to pave the 100 same. In this operation the paving material in its plastic form is poured into the ditch in advance of the machine. When the machine advances on this material the second scraping mechanism above described operates to 105 spread the material evenly over the surface.

of the ditch. The roller or third mechanism thereafter rolls the material to compress and form the same into a smooth uniform layer.

The specific mechanism which I have illustrated will now be described in detail by reference to the accompanying drawings.

The main body portion of my machine comprises an elongated frame 1, adapted to be suspended over and extend along the ditch 2. The frame may be supported and reinforced in any manner desired. I have illustrated the frame as supported on a pair of wheels 3 at its forward end and on a tractor 4 at its rear end. The wheels and tractor 10 run on a pair of header-boards or tracks 5 at the edges of the ditch, and the entire machine is adapted to be moved continuously along the tracks by the tractor. Track cleaners 6 provided on the frame keep the 15 tracks clean ahead of the wheels and tractor.

As illustrated in Figs. 1 and 2 of the drawing, three operating mechanisms, A, B, and C, are mounted on the frame 1. Mechanism A includes a pair of endless scrapers (Fig. 20 4) for operating on the sloping portions of the ditch and removing the excess soil, upon the first passage of the machine along the ditch and for carrying and distributing the paving material over the sloping sides of the 25 ditch upon the second passage of the machine along the ditch. Mechanism B includes a blade scraper (Fig. 6) for finish grading the entire surface of the ditch upon the first passage of the machine therealong 30 and for evenly distributing and levelling the paving material over such surface upon the second passage of the machine along the ditch. Mechanism C includes a roller (Fig. 13) for compressing the graded surface to a 35 smooth uniform level upon the first passage of the machine and for compressing and forming the soft paving material into a smooth uniform layer upon the second passage of the machine. These three mechanisms will now be described in detail.

The mechanism A is shown particularly in Figs. 3 and 4 of the drawing. A pair of supports 7 and 7' are pivotally mounted on shafts 8 and 8' respectively, at the opposite 50 edges of the frame 1. An endless carrier 9 having a plurality of scraping elements 10 thereon, passes around each support and over a sprocket wheel 11 on the shaft 8. The shafts 8 and 8' are respectively driven from shafts 12 and 12' through chains 13 and 13'. The shafts 12 and 12' are driven from a motor 14 through worm gearing 15 and gears 16.

The supports 7 and 7' extend downward 60 into the ditch as shown in Fig. 4 and may be adjusted vertically about the shafts 8 and 8' by the following mechanism: Toothed racks 17 and 17', secured to the supports, are in mesh with pinions 18 and 18'. The shafts 65 on which these pinions are mounted are con-

nected by a sprocket chain 19. The pinions can be rotated and the supports adjusted vertically by means of a handle 20 connected thereto through gearing 21 and a worm and worm gear 22.

The mechanism B is shown particularly in Figs. 5 to 12, inclusive. A carriage 23 is movably supported on the frame 1 by rollers 24. The carriage has a downwardly extending portion 25, within which is supported for vertical adjustment a frame 26, including a guiding track 27. This track extends transversely of the frame 1, and is of the general shape it is desired to form the surface of the ditch transversely.

The frame 26 is supported for vertical adjustment on the carriage by means of four screws 28. These screws are connected to the frame and supported by rotating nuts on the carriage. A motor 29 on the carriage has a worm connected with a worm wheel 30 carrying a sprocket wheel 31. An endless chain 32 extends about the sprocket wheel 31, and sprocket wheels 33 connected to the screw-supporting nuts. The frame 26 can, therefore, be adjusted vertically by operating the motor 29.

The carriage 23 carries a second motor 34 having a worm and worm wheel connection 35 with a shaft 36. Pinions 37 and 37' on the ends of this shaft are in toothed engagement with rack teeth 38 and 38' on the frame 1. The carriage can therefore be moved along the frame 1 by operating the motor 34.

A scraper, including a blade 39 mounted on a carrier 40, is carried by rollers 41 on the track 27 (Fig. 8). A pair of endless chains 42 and 43 extend along the length of the track, and over sprocket wheels 44 and 45 on a shaft 46. The chain 42 is connected to the carrier 40 by means of a pin 47 on the chain 42 (Figs. 7 and 12).

The chain 43 rides over two idlers, 48 and 49, and around a sprocket 50 fast on a shaft 51. A sprocket 52 on the other end of shaft 51 is connected by a chain to a sprocket on a shaft 53 having a worm 54 thereon in mesh with worm gear teeth on a ring 55. This ring 55 carries the blade 39 and is rotatable on a vertical axis in the carrier 40. The construction is such that when both chains 42 and 43 are operated by the shaft 46, the carrier 40 is moved along the track 27 without any rotary movement being imparted to the ring 55. However, when the chain 42 is stationary and the chain 43 is operated, the ring is rotated through the connections described.

The shaft 46 is driven by a motor 56 on the carriage 23 connected to the shaft by a worm and worm wheel 57. The sprocket 45, over which the chain 43 rides, is fast on the shaft 46. The sprocket 44, over which the chain 42 rides, is loose on the shaft 46, and can be clutched thereto by a clutch 58 on one side of the sprocket 44. A

brake band 59 is provided on the opposite side of this sprocket. The clutch and brake band are connected, respectively, to arms 60 and 61 carried by the carriage 23, and splined to a rod 62 extending along the frame 1. The rod is connected at one end to a controlling lever 63 on the frame 1 (Fig. 2). The construction is such that movement of the lever in one direction 10 engages the clutch and applies the brake, and movement thereof in the opposite direction disengages the brake and engages the clutch. The two chains 42 and 43 can, therefore, be operated simultaneously to move the carriage 40 without rotating the blade-holding ring 55, or the chain 42 can be stopped and the chain 43 operated to adjust the angular position of the blade 39.

The mechanism C is shown in Figs. 1, 20 and 13. Adjacent its rear end, the frame 1 carries downwardly extending portions 64, within which is supported for vertical adjustment a frame 65, including a guiding track 66, extending transversely of the frame 1. This track with its supporting and adjusting mechanism is similar to the track 27 above described, and its shape longitudinally conforms to the shape it is desired to form the surface of the ditch 30 transversely. A roller 67 is mounted in this track in substantially the same manner in which the scraper 39 is mounted (Fig. 8). An endless chain 68 extends along the track and is connected to the roller and operatively connected to a motor 69 carried by the frame 65. The motor can be operated in either direction to draw the roller along the track in either direction.

The frame 65 is supported by four screws 40 70 in substantially the same manner as the frame 26 is supported (Fig. 6). These screws are supported by rotating nuts on the frame 1. A motor 71 on the frame 1 has a worm and worm wheel connection 71 with a sprocket wheel 73. An endless chain 74 extends about the sprocket 73 and four sprockets 75 connected to the screw supporting nuts. The frame 65 can, therefore, be adjusted vertically by operating the motor 71. As shown in Fig. 13, the track 66 conforms in shape to the cross-sectional shape of the ditch, and with the frame adjusted to the proper vertical positions, the roller can be traversed along the track in a manner to pack either the graded surface of the ditch or the paving material to a uniform level throughout its entire surface.

Old ditches are frequently provided with water controlling gates and other obstacles 60 offering obstruction to the passage of the mechanisms A, B and C. When operating on such ditches the mechanism A can be raised to a clearing position by means of the racks and pinions 17-18. Mechanisms B and C can also be raised to a clearing po-

sition by disconnecting the supporting bearings for the right-hand screws 70 and 28 from the frame 1, (Fig. 2) and pivoting the frames 64 and 26 upwardly about their pivoted support on the left-hand screws 70 70 and 28.

The entire machine is preferably controlled from one position thereon, and, as shown in Figs. 1 and 3, this position is preferably at the forward end of the machine. 75 A platform 76 is provided adjacent to the endless scraper 7. A seat 77 is provided for the operator on this platform, and the several controls for the various mechanisms are arranged around this seat. The motors 80 14, 29, 34, 56, 69 and 71 are adapted to be controlled by controls 78, 79, 80, 81, 82 and 83, respectively. The clutch and brake controlling lever 63 extends upwardly through the platform adjacent to the seat, and adjacent to the lever 63 is a lever 84 for controlling the movements of the tractor 4.

It is believed that the construction, operation, and advantages of my machine will be apparent without further description 90 thereof. Very briefly, the operation is as follows:

The ditch being previously formed in the rough, my machine straddles the ditch and is moved continuously therealong under the power of the tractor 4 in the direction of the arrow (Figs. 1 and 2). The endless scrapers shown in Fig. 4 and at A in Fig. 2 finish grade the sloping portion of the ditch and remove the excess soil. The 100 scraping blade 39 (Fig. 6) shown at B, next operates on the ditch to finish grade the entire surface thereof. The motor 56 operates to move this blade along the track 27 transversely of the ditch and to change 105 the angular position of the blade when desired. The motor 34 operates to move the blade and its carriage longitudinally of the ditch. The mechanism C, including the roller 67, thereafter rolls the graded surface to a smooth uniform level.

The ditch now being properly graded and rolled to a uniform level, the machine is again run therealong to pave the same. In this operation the paving material in its 115 plastic form is poured into the ditch considerably in advance of the machine. When the machine advances on this material the endless scrapers at A are elevated to clear the material and are left in inoperative position. The scraping blade 39 of the mechanism B is adjusted the proper distance above the grade line and operates on the material to uniformly level and spread the same. The mechanism C thereafter rolls and 120 packs the paving material to form a smooth uniform layer 85. This operation is illustrated in Fig. 2. The paving material is preferably asphalt and when using such material the roller 67 is preferably heated 125 130

to provide a smoother paving surface. This heating is accomplished by an oil burner provided with fuel from a tank 86. (Fig. 13).

5 It may be desired to use the machine on ditches varying in width. In the accompanying drawings, I have shown in a general manner how this can be accomplished. It will be noted, as illustrated in 10 Figs. 1, 3, 4, 5, 6 and 13, that the midportions of the transversely extending parts of the frame 1 and of the supports for the mechanisms A, B and C are removably secured to the various parts of the frame-work of the 15 machine by bolts and plates. These midportions can be removed, and when the parts are reassembled without such portions, the machine, being narrower, is adapted to operate on a narrower ditch. The transversely 20 extending shaft 36 is also provided with a detachable central portion 36^a, which can be removed to adapt the machine to a narrower ditch. It should be understood that I have herein illustrated only one such adjustment, and that further and finer adjustments 25 may be provided for, if desired.

What I claim as new and desire to secure by Letters Patent is:

1. A ditch grading machine comprising 30 the combination of an elongated frame adapted to be suspended over and extend along a ditch, supporting means at the sides of the frame adapted to be supported on and travel along the edges of the ditch, power 35 means for moving the frame along the ditch, a pair of endless travelling scrapers mounted respectively on the sides of the frame and extending transversely of and downwardly into the ditch and adapted to scrape the 40 sloping surfaces thereof, and means for adjusting the angular position of the scrapers vertically relative to the frame.

2. A ditch grading machine comprising 45 the combination of an elongated frame adapted to be suspended over and extend along a ditch, a pair of supports pivotally mounted respectively on the sides of the frame and extending transversely into the 50 ditch, an endless carrier having a plurality of scrapers thereon on each support, a rotary element at the pivotal center of each support for driving the carrier, and means for adjusting the supports vertically about the 55 said pivots.

3. A ditch grading machine comprising 60 the combination of an elongated frame adapted to be suspended over and extend along a ditch, supporting means for the frame adapted to rest on the edges of the ditch, a carriage mounted to travel on the frame longitudinally thereof and extend downwardly into the ditch, a scraper carried on the lower portion of the carriage, 65 means for adjusting the scraper vertically,

and means for moving the scraper in both directions transversely of the ditch and for causing the scraper to traverse a pre-determined path conforming to the shape it is desired to impart to the surface of the ditch 70 transversely.

4. A ditch grading machine comprising the combination of an elongated frame adapted to be suspended over and extend along a ditch, supporting means for the 75 frame adapted to rest on the edges of the ditch, a carriage mounted to travel on the frame longitudinally thereof and extend downwardly into the ditch, a track carried by the lower portion of the carriage, extending transversely of the ditch and of the general shape it is desired to form the surface of the ditch transversely, a scraper carried by the track, means for moving the scraper along the track in both directions, 80 and means for adjusting the scraper vertically.

5. A ditch grading machine comprising the combination of an elongated frame 85 adapted to be suspended over and extend along a ditch, supporting means for the frame adapted to rest on the edges of the ditch, a carriage mounted to travel on the frame longitudinally thereof and extend downwardly 90 into the ditch, a track carried by the lower portion of the carriage, extending transversely of the ditch and of the general shape it is desired to form the surface of the ditch transversely, a vertically extending scraping blade carried by the track, means for moving the blade along the track in both directions, means for changing the angular position of the blade, and means for adjusting the blade vertically.

6. A ditch grading machine comprising 105 the combination of an elongated frame adapted to be suspended over and extend along a ditch, supporting means for the frame adapted to rest on the edges of the ditch, a carriage mounted to travel on the frame longitudinally thereof and extend downwardly into the ditch, a scraper carried on the lower portion of the carriage, means 110 for adjusting the scraper vertically, means for moving the scraper transversely of the ditch and for causing the scraper to traverse a pre-determined path conforming to the shape it is desired to impart to the surface of the ditch transversely, and power means 115 under the control of the operator for performing the carriage moving and both said scraper moving operations.

7. A ditch grading machine comprising 125 the combination of an elongated frame adapted to be suspended over and extend along a ditch, supporting means for the frame adapted to rest on the edges of the ditch, a carriage mounted to travel on the frame longitudinally thereof and extend downwardly into the ditch, a track carried 130

- by the lower portion of the carriage, extending transversely of the ditch and of the general shape it is desired to form the surface of the ditch transversely, a scraper carried by the track, means for adjusting the scraper vertically, and power-operated means, including an endless chain, for moving the scraper along the track in both directions and for changing the angle of the scraper.
8. A ditch grading machine comprising the combination of an elongated frame adapted to be suspended over and extend along a ditch, supporting means for the frame adapted to rest on the edges of the ditch, a carriage mounted to travel on the frame longitudinally thereof and extend downwardly into the ditch, a track carried by the lower portion of the carriage, extending transversely of the ditch and of the general shape it is desired to form the surface of the ditch transversely, a roller carried by the track, means for moving the roller along the track, and power means under the control of an operator for operating the roller and for adjusting the roller vertically.
12. A ditch grading and lining machine comprising the combination of an elongated frame adapted to be suspended over and extend along a ditch, supporting means for the frame, adapted to rest on the edges of the ditch, a carriage mounted to travel on the frame longitudinally thereof and extending downwardly into the ditch, a scraper carried by the carriage, means for moving the scraper over the surface of the ditch to grade the same and for adjusting the scraper vertically, a support carried by the frame and extending downwardly into the ditch, a roller carried by the support, means for adjusting the roller vertically, and power-operated means for rolling and guiding the roller over the surface of the ditch.
13. A ditch grading and lining machine comprising the combination of an elongated frame adapted to be suspended over and extend along the ditch, supporting means for the frame adapted to rest on the edges of the ditch, mechanism mounted on the frame and carrying power-operated means for engaging the surface of the ditch to grade the same, a support spaced from the said mechanism, carried by the frame and extending downwardly into the ditch, a roller carried by the support, means for adjusting the roller vertically, and power-operated means for rolling and guiding the roller over the surface of the ditch.
14. A ditch grading and lining machine comprising the combination of an elongated frame adapted to be suspended over and extend along the ditch, supporting means for the frame adapted to rest on the edges of the ditch, power means for moving the frame along the ditch, mechanism mounted on the frame and carrying means for engaging the surface of the ditch to grade the same, a support spaced from the said mechanism, carried by the frame and extending downwardly into the ditch, a roller carried by the support, means for adjusting the roller vertically, means for rolling and guiding the roller over the surface of the ditch, and electric motor means under manual control for operating the grading means and roller.
11. A ditch grading and lining machine comprising the combination of an elongated frame adapted to be suspended over and extend along the ditch, supporting means for the frame adapted to rest on the edges of the ditch, mechanism mounted on the frame and carrying power-operated means for engaging the surface of the ditch to grade the same, a support spaced from the said mechanism, carried by the frame and extending downwardly into the ditch, a roller carried by the support, means for adjusting the roller vertically, means for rolling and guiding the roller over the surface of the ditch, and electric motor means under manual control for operating the grading means and roller.

15. A ditch grading and lining machine comprising the combination of an elongated frame adapted to be suspended over and extend along the ditch, supporting means for the frame adapted to rest on the edges of the ditch, mechanism mounted on the frame and carrying power-operated means for engaging the surface of the ditch to grade the 35 same, and power-operated mechanism carried by the frame for compressing and smoothing the graded surface, the said mechanisms being adapted upon a second passage of the machine over the ditch to 40 operate upon a paving material therein to evenly distribute and form the same into a smooth uniform compressed layer over the graded surface.
16. A ditch grading and lining machine 45 comprising the combination of an elongated frame adapted to be suspended over and extend along the ditch, supporting means for the frame adapted to rest on the edges of the ditch, mechanism mounted on the frame and carrying power-operated means for engaging the surface of the ditch to grade the same, and power-operated mechanism carried by the frame and including a roller for compressing and smoothing the graded surface, the said mechanisms being adapted upon a second passage of the machine over the ditch to operate upon a paving material 50 therein to evenly distribute and roll the same into a smooth uniform compressed layer over the graded surface.
17. A ditch grading and lining machine 55 comprising the combination of an elongated frame adapted to be suspended over and extend along the ditch, supporting means for the frame adapted to rest on the edges of the ditch, mechanism mounted on the frame and carrying power-operated means for engaging the surface of the ditch to grade the same, and power-operated mechanism carried by the frame and including a roller for compressing and smoothing the graded surface, the said mechanisms being adapted upon a second passage of the machine over the ditch to operate upon a paving material 60 therein to evenly distribute and roll the same into a smooth uniform compressed layer over the graded surface.
16. A ditch grading and lining machine comprising the combination of an elongated frame adapted to be suspended over and extend along the ditch, supporting means for

FRED E. GREENE.
